UNITED STATES PATENT OFFICE.

WILLIAM L. RUDD AND WILLIAM E. STOUT, OF CHICAGO, ILLINOIS.

COMBINED OILER AND WIPER FOR PISTON-RODS.

No. 838,650.

Specification of Letters Patent.

Patented Dec. 18, 1906.

Application filed November 27 1905. Serial No. 289,252.

To all whom it may concern:

Be it known that we, WILLIAM L. RUDD and WILLIAM E. STOUT, citizens of the United States, and residents of Chicago, in the county of Cook and State of Illinois, have invented certain new and useful Improvements in a Combined Oiler and Wiper for Piston-Rods, of which the following, when taken in connection with the drawings accompanying and forming a part hereof, is a full and complete description, sufficient to enable those skilled in the art to which it pertains to understand, make, and use the same.

15 The object of this invention is to obtain an apparatus whereby the piston-rod of an engine, particularly of a rapid-running engine, will be continuously oiled and cleaned, and thereby the packing of the piston will be preserved for a much greater length of time than otherwise can be done, and also a cheaper grade of packing can be used.

We have found in practice that in some large engines in which the rotation of the 25 crank-shaft is from two hundred and sixty to three hundred revolutions per minute a high-grade packing has heretofore been required in the stuffing-box of the piston-rod and that the same has necessarily been renewed not less than two times a week, and 30 on the same engines when our oiler and cleaner has been attached thereto a low-grade packing has been used and the same has not required repacking oftener than once 35 in ten or more weeks.

In the drawings referred to as accompanying and forming a part of this specification, Figure 1 is an elevation of the end of a piston-cylinder and a device embodying our invention attached thereto. Fig. 2 is a side elevation of one end of a piston-cylinder with a device embodying our invention attached thereto. Fig. 3 is a perspective of a device embodying our invention, on an enlarged scale. Fig. 4 is a front elevation of the end of a piston-cylinder having a round gland to the piston-rod packing-box and our device attached thereto. Fig. 5 is a side elevation of one end of such cylinder with our device 45 attached thereto, showing the combined waste and oil box of the device in cross-section; and Fig. 6 is a perspective of the clamp shown in Figs. 4 and 5, on an enlarged scale.

50 A reference-letter applied to designate a

given part is used to indicate such part throughout the several figures of the drawings wherever the same appears.

A is the end of a cylinder of an engine.

B is the gland of the stuffing-box of cylinder A.

CC are the bolts by which the stuffing-box is adjusted.

D is the piston-rod of the engine.

E is the base of the device embodying our invention. Base E is attachable directly to gland B in those engines where such gland is rectangular and is secured to the cylinder by bolts C. In those engines where gland B is circular, as B', Figs. 4 and 5, we make an additional base, as F, Fig. 6, and attach such additional base to the stuffing-box G, as by bolt F, and place base E on such additional base. When the cylinder A and piston-rod D are of the type of engines known as "horizontal," no fastening of base E to gland B or to subbase F is required; but when the device is attached to a vertical engine bolts H H, Fig. 5, are used. Bolts H H extend, respectively, through holes therefor in base E and subbase F, where the subbase is used, and through like holes in gland B if no subbase is used. Any mode of fastening base E to the engine-cylinder equivalent to bolts H H may be substituted therefor.

I is the receptacle of the device embodying this invention and is open at both ends. The lower end walls are curved to substantially correspond with the periphery of the piston-rod D adjacent thereto.

J, Fig. 5, is cotton waste or equivalent material in receptacle I. Material J is forced into the receptacle I, so that oil, as K, Fig. 5, will not readily flow therethrough. When packed in such receptacle, as described, and so as to extend a slight distance below receptacle I to come in contact with piston-rod D as such piston moves back and forth thereunder, the oil will gradually flow through the packing J and lubricate the piston-rod, while at the same time the piston-rod is wiped by the packing and kept clean.

The packing J may consist of felt or other fibrous material through which the oil will slowly percolate.

When the device is attached to a vertical engine, the packing J is saturated with oil, and any excess of oil will run from the receptacle I.

Having thus described our invention, what we claim as new, and desire to secure by Letters Patent, is—

1. In a combined oiler and wiper, a receptacle open at both ends, fibrous material packed in the receptacle to extend slightly below the receptacle to constitute the bottom thereof and to near the top of the receptacle, such receptacle adapted to hold oil above the fibrous material, an additional base having the side edges bent up to obtain a rectangular head corresponding with the inverted-U-shaped base and fitting thereto, and means to attach such additional base to the stuffing-box of an engine.

2. In a combined oiler and wiper, a receptacle open at both ends, fibrous material

packed in the receptacle to extend slightly below the receptacle to constitute the bottom thereof and to near the top of the receptacle, such receptacle adapted to hold oil above the fibrous material, an additional base having the side edges bent up to obtain a rectangular head corresponding with the inverted-U-shaped base and fitting thereto, and means to attach such additional base to the stuffing-box of an engine.

WILLIAM L. RUDD.
WILLIAM E. STOUT.
